(57) **CLAIM**

The ornamental design for a walking slide mill, as shown and described.

DESCRIPTION

FIG. 1 is a front perspective view showing our new design for a walking slide mill;

FIG. 2 is a left side elevational view, the right side being a mirror image thereof;

FIG. 3 is a front elevational view;

FIG. 4 is a rear elevational view;

FIG. 5 is a top plan view;

FIG. 6 is a cross sectional view taken along lines 6-6 of FIG. 5;

FIG. 7 is a bottom plan view; and,

FIG. 8 is a rear perspective view.

The broken line drawings of the person and handles are for illustrative purposes only and form no part of the claimed design.

UNITED STATES PATENT AND TRADEMARK OFFICE
CERTIFICATE OF CORRECTION

PATENT NO. : D723,636 S
APPLICATION NO. : 29/470086
DATED : March 3, 2015
INVENTOR(S) : Paul G. Kahmann et al.

Page 1 of 1

It is certified that error appears in the above-identified patent and that said Letters Patent is hereby corrected as shown below:

Title page, below the DESCRIPTION, delete lines 12-14 and insert the following:

--The broken lines on the walking slide mill are for the purpose of illustrating portions of the article that form no part of the claimed design. The broken line showing of a person and handles is for the purpose of illustrating environment that forms no part of the claimed design.--

Signed and Sealed this
Ninth Day of June, 2015

Michelle K. Lee
Director of the United States Patent and Trademark Office
